(57) **CLAIM**

The ornamental design for an accessory for electronic device, as shown and described.

DESCRIPTION

FIG. 1 is a perspective view including a front, bottom, and side of an accessory for electronic device in an environment of use;

FIG. 2 is a front elevation view thereof;

FIG. 3 is a rear elevation view thereof;

FIG. 4 is a side elevation view thereof;

FIG. 5 is an opposite side elevation view thereof;

FIG. 6 is a top plan view thereof;

FIG. 7 is a bottom plan view thereof;

FIG. 8 is a perspective view including a front, bottom, and side of the accessory for electronic device in an environment of use, with components separated from each other for clarity of disclosure;

FIG. 9 is a perspective view including a front, bottom, and side of the corner loop mount portion of the accessory for electronic device;

FIG. 10 is a front elevation view thereof;

FIG. 11 is a rear elevation view thereof;

FIG. 12 is a side elevation view thereof;

FIG. 13 is an opposite side elevation view thereof;

FIG. 14 is a top plan view thereof;

FIG. 15 is a bottom plan view thereof;

FIG. 16 is a perspective view including a front, bottom and side of the corner loop mount portion of the accessory for electronic device with components separated from each other for clarity of disclosure;

FIG. 17 is a perspective view including a front, top and side thereof, with components separated from each other for clarity of disclosure;

FIG. 18 is a side elevation view thereof, with components separated from each other for clarity of disclosure;

FIG. 19 is an opposite side elevation view thereof, with components separated from each other for clarity of disclosure; and,

FIG. 20 is a top perspective view thereof, with components separated from each other for clarity of disclosure; and,

(Continued)

FIG. 21 is a bottom perspective view thereof with components separated from each other for clarity of disclosure. The dashed broken lines in FIGS. 1-8 represent environmental subject matter that forms no part of the claimed design. The straight dot-dash broken line in FIGS. 8 and 16-17 represents the course along which the components of the accessory for electronic device are separated from each other, and forms no part of the claimed design.
